UNITED STATES PATENT OFFICE.

GORDON DON HARRIS, OF STAMFORD, CONNECTICUT, ASSIGNOR TO THE INDUSTRIAL DRYER CORPORATION, OF STAMFORD, CONNECTICUT, A CORPORATION OF CONNECTICUT.

DRIER FOR PHOTOGRAPHIC PRINTS AND FILMS.

Application filed March 1, 1926. Serial No. 91,349.

This invention is a drier for various materials, more particularly photographic prints and films, and the object is an apparatus wherein air at a desired temperature and humidity may be circulated at the required velocity and in the required volume for effecting the exchange of heat for moisture to the end that prints and films may be dried rapidly and uniformly and without curling of the margins thereof.

The apparatus of my invention is adapted for use interchangeably with films and prints, and in drying films they are suspended within a chamber for exposure to contact with the circulating air, whereas prints are or may be forcibly pressed on or squeegeed upon plate-like members adapted also for exposure to the circulating air. Provision is made for conditioning the air as to its moisture content during the cycles of its recirculation within the apparatus, and to this end, a desired volume of moist air is discharged and a like volume of fresh atmospheric air is supplied at and during the recirculation of the drying atmosphere, thus precluding the flow of air having excess humidity into contact with the material under treatment.

Other functions and advantages of the invention will appear from the following description taken in connection with the drawings, wherein—

Figure 1 is a vertical sectional elevation of the apparatus adapted for drying photographic prints.

Figure 2 is a similar view of the apparatus adapted for drying suspended photographic films.

Figure 3 is a vertical section of another embodiment of the invention adapted for drying photographic films; and

Figure 4 is a sectional plan view of the apparatus shown in Figure 3.

The apparatus shown in Figures 1 and 2 is constructed for use either for prints or films by a simple interchange of some of the parts. A housing A is provided with vertical partition walls B parallel to two of its sides, said partition walls being spaced relatively to the housing walls to produce flues or ducts C. These ducts extend from the bottom nearly to the top, and they provide for the upward flow of a drying medium, and for the delivery of such medium to the

upper portion of the housing. In the housing, at the bottom thereof, are provided ejection ports, a for the outflow of some of the moist drying medium, the volume of the escaping atmosphere being determined by the area of the ports.

Near the top, the housing is formed with inlet ports, b, which open into the flues C and they operate to admit a determined volume of fresh atmospheric air to the drying atmosphere as the latter returns to the chambers of the apparatus within which the material is adapted to be contained.

D is a fan positioned within the upper part of the housing and mounted to rotate on a vertical axis, whereby the rotation of the fan blows the drying atmosphere downwardly into one or a plurality of chambers E, E', contained within the housing.

The partition walls B are shown as having a series of ledges, c, d, e, f, the utility of which is that they afford supports for the elements used interchangeably within the apparatus for exposing prints or films to the flow of the drying medium. As shown in Figure 1, a horizontal perforated or slotted rack, F, is adapted to be supported by the ledges, d, at the bottom part of chamber E, said rack F having a plurality of holders or clips, g, for retaining a number of plate-like members G within the chamber E.

Ledges, f at or near the bottom of the partition walls afford means for supporting another perforated or slotted rack H, the latter being near the bottom part of chamber E', said rack H having holders or clips h for retaining the plate-like members G' within the chamber E'.

Ledges e are below the ledges d, relatively close thereto, and they support a foraminous or perforated tray, I, below the rack F and across the upper part of chamber E', said tray having a fibrous pad, I', which is composed of loosely woven absorbent material adapted to be saturated with a suitable liquid for imparting humidity to the drying atmosphere adapted to be circulated within said chambers, E, E'. The tray with the moistener permits the relatively free downward flow of the drying atmosphere under the impulse created by the rotation of the fan, the interstices of the tray and the moistener being such as to afford small obstruction to the flow of the atmosphere.

The moistener and tray are adapted to be charged with liquid in any manner preferred. The racks, F, H, and tray, I, are demountable from the ledges d, e, f, respectively, and they are removable at will from the chambers E, E', through suitable doors (not shown) provided in the walls of the housing. The fibrous open mesh moistener acts, also, as a medium for filtering the 10 circulating drying medium for eliminating particles of dust, etc., and thus overcomes lodgment of foreign matter upon the surfaces of the prints or films.

Intermediate the fan D and the load with- 15 in the upper chamber E are vanes or baf- fles J for diverting the flow of air from the fan, and for distributing the same uniformly over the prints or films. These vanes are fixedly supported within the housing di- 20 rectly below the fan, and they are variously inclined with reference to the vertical axis of the chamber E, and to the plate-like mem- bers G, whereby the vanes are in the line 25 of flow of the air blown downwardly by the fan, the vanes acting to divert the air to- ward the sides, middle, and intermediate areas of the chamber in a manner to equal- ize the flow downwardly.

The apparatus of Figure 1 is used for 30 drying photographic prints which are pressed forcibly upon the surfaces of the plate-like members G, G', or squeegeed thereupon, in order to be in a flat, smooth condition during the drying operation, said 35 plates having polished surfaces to impart a desirable glossy finish to the sensitized sur- faces. The racks, F, H, and moistener tray, I, are removable at will to obtain access to the members G, G', and moistener I', to the 40 end that the prints in a wet condition may be squeezed onto the members when the lat- ter are dismounted from the racks, as well as to moisten the fibrous material on the tray as and when required. The trays are 45 placed in the holders of the racks, and the loaded trays are inserted into the chambers E, E', with the tray I between the racks. The fan is driven to circulate the drying medium by blowing it downwardly within 50 chambers E, E', and exhausting the medium by drawing it upwardly through the flues C, thus recirculating the medium in order to utilize an atmosphere having a desired moisture content for the efficient and rapid 55 elimination of moisture from the prints. In the downflow of air from the fan, it is di- 60 versed by the vanes J, and its flow equalized in the several parts of chambers E, E', the atmosphere flowing between the parallel members G, G', and into contacts with the prints thereon. In the cycles of circulation downwardly through the chambers and up- 65 wardly within the flues, some of the moist air flows out of the ports a and fresh air flows through the ports b, and the moist air

is mixed with the fresh air by the action of the fan, the mixture constituting the drying atmosphere which is conditioned to pre- 70 clude saturation by such atmospheric ad- mixture.

For using the apparatus in the drying of photographic films, the racks F, H, and the tray, I, are removed from the chambers E, E', by sliding said parts off the ledges d, e, f, and thereupon a bar or rail K is in- 75 serted into the upper part of the chamber E², in Figure 2, in order to provide for the suspension therein of the elongated films, indicated at L. The bar or rail K occupies a horizontal position below the vanes J, and 80 rests upon the ledges c provided near the top of the chamber E². The films are hung from the rail K by suitable hooks, as k, and they are suspended freely within the chamber E² for exposure to the atmosphere 85 blown downwardly and recirculated by the fan D. The atmosphere is conditioned by the discharge of some of the moist air through ports a and the admixture of fresh air admitted through ports b, such down- 90 flowing atmosphere from the fan being di- 95 verted by the vanes J, all as described here- tofore.

In the apparatus of Figures 1 and 2, the fan D is positioned interiorly with respect 95 to the housing, but in Figures 3 and 4 there is shown another embodiment, wherein a combined blower and exhaust O is ar- ranged exteriorly of said housing and is mounted for rotation on a horizontal axis. 100 Said blower and exhaust O is encased within a casing o erected upon the housing A; from this fan casing leads a flue o' at- 105 tached to the housing for delivering the atmosphere into the top chamber P which is separated by a perforated partition p from the chamber E, the vanes J of Figures 1 and 2 being omitted and partition p sub- 110 stituted therefor as a means for equalizing the flow of air downwardly upon the prints or films.

The apparatus of Figures 3 and 4 is shown as equipped with racks F, H, for the members G, G', adapted to contain prints, indicated at 10 in Figure 3, but, obviously, 115 the racks and the tray may be removed in order that a rail such as K may be arranged therein for suspending long films within the chamber of said housing. Said appa- 120 ratus of Figures 3 and 4 is constructed with a single return duct or flue Q, positioned at one side thereof, said duct being connected to the lower part of the chamber, and said duct having an exit port a, and an inlet port b. The duct leads upwardly from the hous- 125 ing, and it is enlarged in cross section to produce a chamber q opening into the intake of the combined blower and exhaust O, and within this chamber q are positioned de- 130 flectors q', the latter being above the fresh

air intake *b* for retarding in a measure the flow of moist and fresh air into the chamber *g* under the suction created by the rotation of the blower and exhauster.

5 Having thus fully described the invention, what I claim as new and desire to secure by Letters Patent is:

10 1. A drier of the class described embodying a chamber and a flue for the circulation of a drying atmosphere, means for supporting material within the chamber, a blower for circulating the atmosphere downwardly within said chamber, and means for diverting the downflow of said atmosphere and for 15 equalizing the flow within said chamber.

20 2. In a drier of the class described, a chamber, a blower for circulating a drying atmosphere downwardly within said chamber, a flue connected with the chamber and to the intake to said blower, said flue having an air exit and an air inlet, whereby the recirculated atmosphere may be conditioned as to its moisture content, and means for 25 supporting material within said chamber.

30 3. In a drier of the class described, a foraminous tray therein, a plurality of racks positioned within the chamber at the respective sides of the tray, said racks having means for supporting a series of plate-like members, means for blowing a drying atmosphere downwardly within the chamber, return ducts having eduction and intake

ports, and means for diverting the downflow of the drying atmosphere and equalizing the flow thereof within said chamber. 35

4. In a drier of the class described, a chamber, a blower for circulating air downwardly therein, a return flue provided with an air outlet and an air inlet, a rack positioned within the chamber and removable 40 therefrom, said rack having means for supporting a plurality of plate-like members, and means for diverting the downflow of air within said chamber.

45 5. A drier of the class described embodying a housing provided with partition walls forming a chamber and a plurality of return flues, a tray mounted removably within said chamber, a plurality of racks removable from said chamber, means for blowing air 50 downwardly within the chamber, and air deflecting means positioned intermediate the blower and one of said racks.

55 6. A drier of the class described embodying a housing provided with a chamber and a return flue, the latter having an air outlet and an air inlet, a blower connected with the return flue and operating for blowing air downwardly within the chamber, means 60 for supporting material in the chamber, and air deflecting means below said blower.

In testimony whereof I have hereto signed my name this 26th day of February, 1926.
GORDON DON HARRIS.
